UNITED STATES PATENT OFFICE.

JULIUS PEGEL, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 14,854, dated March 4, 1884.

Application filed January 28, 1884. Term of patent 3½ years.

To all whom it may concern:

Be it known that I, JULIUS PEGEL, of New York city, in the State of New York, have invented a new and original Design for Carpets, 5 of which the following is a specification, reference being had to the accompanying photograph, which forms a part of the same.

The invention relates to a design to be worked into or upon surfaces, such as carpets or similar 10 fabrics; and it consists in the novel configuration and grouping of figures herein specifically shown and claimed.

The accompanying photograph is a face view 15 of a carpet, showing my new design.

The design consists of two large and two smaller flower groups that are disposed over the face of the design so as to interlock and loosely fill it. The group shown in the lower 20 center of the photograph is a large mass of

open flowers and leaves, with large projecting 20 fern-sprays. The group shown in the upper center of the photograph is a large rose with massed leaves and star-shaped flowers. It has a secondary mass of flowers to the left above. The group shown at the left center and right 25 upper and lower corners, and at the right center and left lower corner, of the photograph, respectively, are smaller, but are open flowers and leaves massed in same general way as the larger groups.

30 I claim—

The design for a carpet, substantially as shown and described.

JULIUS PEGEL.
